DESIGN FOR A WOVEN TEXTILE FABRIC

John Walther, New York, N. Y.

Application January 5, 1945, Serial No. 117,259

Term of patent 7 years

(Cl. D92—1)

To all whom it may concern:

Be it known that I, John Walther, a citizen of the United States of America, residing in New York, county of New York and State of New York, have invented a new, original, and ornamental Design for a Woven Textile Fabric, of which the following is a specification, reference being had to the accompanying drawing, forming part thereof.

The figure on the drawing is a plan view of a woven textile fabric showing my new design.

The characteristic features of my design reside in a fabric of herring bone-type weave having relatively narrow stripes composed of a series of closely spaced V-like elements placed at, and with the apices of the V-like elements pointing in the direction of, the apices of the herring bone-type weave and a narrow contrastingly colored rope-like stripe placed mid-way between the stripes of V-like elements as shown.

I claim:

The ornamental design for a woven textile fabric, substantially as shown and described.

JOHN WALTHER.
